DESIGN FOR A POKER CHIP AND PLAYING CARD HOLDER

Donald J. Smith, Los Angeles, Calif.

Application April 16, 1945, Serial No. 119,044

Term of patent 7 years

(Cl. D34—5)

To all whom it may concern:

Be it known that I, Donald J. Smith, a citizen of the United States, residing at Los Angeles, in the county of Los Angeles and State of California, have invented a new, original, and ornamental Design for a Poker Chip and Playing Card Holder, of which the following is a specification, reference being had to the accompanying drawing, forming part thereof.

Fig. 1 is a top plan view, of a poker chip and playing card holder embodying my new design, with the cover removed.

Fig. 2 is an exploded perspective view thereof.

I claim:

The ornamental design for a poker chip and playing card holder, substantially as shown.

DONALD J. SMITH.
